BOOM SPRAYER

Isaac S. Prescott, Orlando, Fla.

Application August 7, 1946, Serial No. 689,028

3 Claims. (Cl. 299—73)

1

This invention relates to sprayers and more particularly to boom sprayers such as commonly used for the spraying of orchards and the like.

An object of the invention is to provide an improved and simplified sprayer which can be easily manipulated by a single operator.

A further object of the invention is to provide an improved boom sprayer with great flexibility of adjustment so that the spray shower can be selectively adjusted to cover the tree from top to bottom and can be further manipulated to direct the spray shower as the vehicle upon which the sprayer is mounted passes by the tree to cover the maximum part of the circumference of the tree.

A further object of the invention is to provide an improved sprayer of the type indicated of simplified construction readily adapting itself to cleaning and repair.

Further objects will more particularly appear in the course of the following detailed description.

The invention consists in the novel construction arrangement and combinations of parts hereinafter more particularly described and claimed.

One sheet of drawing accompanies this specification as part thereof in which like reference characters indicate like parts throughout.

Fig. 1 is a plan view;

Fig. 2 is a rear elevation partly shown in cross section;

Fig. 3 is a side elevation of Fig. 2; and

Fig. 4 is a fragmentary cross section taken on the line 4—4 of Fig. 2, parts being shown in elevation.

My boom sprayer as illustrated in the accompanying drawing comprises a tubular standard 1 having its upper end 2 closed and formed with a radially projecting handle 3.

This standard 1 is mounted for axial rotation upon a pedestal 4 provided at its upper end with a bearing 5 and at its lower end with a foot 6 adapted to be secured upon the platform of a truck or other vehicle carrying the tanks, compressors and the like, not illustrated herein.

If desired one of the improved boom sprayers can be mounted on either side or top, front or rear of a truck or other vehicle facing in outward direction and the platform will be constructed of sufficient width and size to accommodate an operator.

Upon the standard 1 is secured a tubular member 7 which is bent on its long axis to an arcuate shape and which may be secured to the standard 2 as herein illustrated as by clips 8—8 or welded as may be preferred. One end of the tubular member 7 is closed as by a cap 9 and the opposite end

is provided with a hose coupling 25 for a hose 20 which extends to the spray tank.

On one face of the tubular member 7 are provided a plurality of threaded nipples 10. It has been found advantageous to provide an ample number of such nipples to permit adjustment of the sprayer heads as may be desired and such of the members 10 as are not actually used with sprayer heads may be closed with caps 11.

Associated with each of the members 10 is a sprayer head which sprayer heads are well known and a preferred form of which, herein illustrated without details, comprises a body part 13 through which extends an adjustment stem 14, the body 15 carrying one or more spaced discharge ports 23 through which the spray emerges. The body part 13 of each sprayer head is formed with a radially projecting threaded nipple 15 and the threaded nipples 15 of the sprayer head and 10 of the tubular member are rotatably connected by two coupling members 16 and 17. The coupling member 17 is interiorly threaded to engage the threaded portion of the two members 15 and 10 and externally threaded to receive the internal thread 25 of the coupling member 16 which is adapted to compress packing rings 19 against the end of the coupling 17, thus assuring a tight joint while at the same time permitting the limited rotation of the sprayer head such as may be desired for adjusting the spray screens selectively as the truck 30 approaches a particular tree.

A guard member 21 is secured by one edge to the standard 2 and has its opposite edge 22 curved to conform substantially with the curvature of the tubular pipe 7, this guard 21 being of sufficient width to extend almost to the line defined by the discharge ports 23 of the sprayer heads and serves to protect the sprayer heads from the branches of trees as the truck carrying the sprayer passes the same.

Various modifications in the precise construction and arrangements of the parts will readily suggest themselves to those skilled in the art but within the scope of the invention as claimed.

Having thus fully described my invention I claim:

1. A boom sprayer comprising a rotatable standard, a tubular member bent on its long axis to arcuate shape and secured by its ends to the standard, said tubular member having an end closed and the other end provided with a hose connection, said tubular member having on one face a plurality of spaced nipples, a plurality of spray heads and means for rotatably mounting said spray heads on said nipples.

2. A boom sprayer comprising a pedestal, a standard having a radially disposed handle, said standard being mounted on the pedestal for axial rotation, a tubular member bent on its long axis to arcuate shape and associated with said standard with the latter coinciding with a chord of said arcuate shaped tube, said tubular member having one end closed and the other end provided with a hose connection, said tubular member having on one side face a plurality of spaced nipples, a plurality of sprayer heads and means for rotatably mounting said spray heads on said nipples.

3. A boom sprayer comprising a rotatable standard, a tubular member bent on its long axis to arcuate shape with its ends extending transversely of and secured to the standard, said tubular member having one end closed and having a hose connection, said tubular member having a plurality of spaced nipples, a plurality of sprayer heads, means for rotatably mounting said sprayer heads on said nipples and a guard member having one edge secured to the standard and its outer edge conforming substantially with the curvature of

the tubular member and extending substantially to the line defined by the outlets of the sprayer heads.

ISAAC S. PRESCOTT.
